UNITED STATES PATENT OFFICE

SAMUEL F. ROCKWELL, OF NORTH ANDOVER, AND HENRY A. OWEN, OF FOXBORO, MASSACHUSETTS, ASSIGNORS TO DAVIS & FURBER MACHINE COMPANY, OF NORTH ANDOVER, MASSACHUSETTS, A CORPORATION OF MASSACHUSETTS

SPINNING FRAME

Application filed August 11, 1930. Serial No. 474,361.

This invention relates to spinning frames, and particularly to means employed therein to prolong the period of usefulness of certain parts which become worn by reason of their contact with the running roving.

The invention is particularly adapted to that type of spinning frame in which a twister tube is employed to induce a temporary reinforcing twist during the drawing operation. In such machines a guiding device, usually a rod of steel, is employed to direct the roving into the tubes at the required angle. The constant passage of roving over the guiding device rapidly wears a groove therein. The groove thus formed tends to prevent the free passage of yarn over the rod, and also subjects the roving to frequent breakage. Furthermore, the grooves in the rod tend to weaken its initial resistance to the tension of the roving to such an extent that, in many cases, the only remedy is to renew the rod.

It is the general object of this invention to distribute the wear of the roving upon the rod over a substantial portion of its area, thus preventing the formation of grooves and thereby prolonging the period of usefulness of the guiding means.

A further object of the invention is to provide a simple and effective means to prevent undesirable wear upon the roving guide and permit the use of ordinary material, such as mild steel, in its construction.

A further object of the invention is to utilize the twister tube itself as a guide-eye to traverse the roving along the guide rod.

A further object of the invention is to provide a spinning frame in which the twister tubes alone are traversed, and in which the upper guide rod, acting to direct the roving into the twister tubes, is fixed to the frame of the machine.

A further object of the invention is to provide a spinning frame in which the upper guide rod may be adjusted vertically.

These and other objects and features will more fully appear from the following description in connection with the accompanying drawings and will be particularly pointed out in the claims.

In the drawings, Figure 1 is a cross-sec-

tional view through a portion of a spinning frame embodying the invention.

Fig. 2 illustrates a portion of the spinning frame showing in plan the parts illustrated in Fig. 1.

Fig. 3 is a plan view illustrating the mechanism for traversing the twister tubes.

In its broadest aspect this invention contemplates a means for causing the roving, as it passes over the upper guide rod, constantly to change its point of contact therewith. The twister tubes in the type of spinning frame illustrated are traversed and they may conveniently be utilized to produce the desired relative movement of the roving along the guide rod.

In the specific embodiment illustrated, the desired result is accomplished by mounting the guide rod in a fixed position near the entering end of the twister tubes. As the tubes moves, therefore, the roving which is threaded therethrough is traversed along the guide rod.

Since the general details of construction of a spinning frame are well known to those skilled in the art it is deemed necessary to illustrate only those portions of a frame which contain the elements of the invention and those which are directly related thereto.

The roving 1, issuing from a suitable source of supply, passes between a pair of driven feed rolls 2 and 3. From the feed rolls it passes into and through a twister tube 4 and thence between a pair of drawing rolls 5 and 6, from which point it is led to a spinning mechanism of any desired construction, which is not shown. The roll 5 is rotatably mounted in a bracket 7 and driven at the proper speed relative to that of the feed rolls to produce the desired draft. The roll 6 is rotatably supported in a bracket 8 which in turn is pivoted upon the bracket 7. The bracket 8 is swung about its pivot to maintain the roll 6 in yielding engagement with the roll 5 by means of the weight 9.

The twister tube 4 may be of any desired construction. A preferred construction, however, is herein illustrated which is similar to the twister tube presented by the U. S. Patent granted to Henry A. Owen, Patent No.

1,770,085, in which the roving 1 is threaded through a central aperture 10 and emerges from the bottom thereof to be engaged by the jaws of a twisting head 11 mounted on the 5 lower end of the tube. From this point the roving leads directly into the bite of the drawing rolls 5 and 6.

The twister tube 4 is rotatably mounted in a bracket 12 which is secured to a movable 10 support 13. The support 13 is slidable longitudinally of the machine in aligned guideways in the brackets 7. The brackets 7 are rigidly fixed to a supporting channel 14 extending throughout the length of the machine. 15 In order to direct the roving into the upper end of the twister tube at the required angle, a guide rod 15 is provided over which the roving passes on its way to the aperture 10 in the twister tube. The rod 15 preferably extends throughout the length of 20 the machine and is adjustably supported in brackets 16 which are secured to the brackets 7 by means of the bolts 17. The rod 15 passes through apertures in a plurality of arms 18 projecting from the upper end of the brackets 16. The inner ends of the arms 18 are reduced in size to form a shoulder 19. The reduced ends of the arms 18 project into a vertical slot 20 in the brackets 16. The extreme inner ends of the arms 18 are threaded 25 to receive nuts 21 by means of which the shoulders 19 of the arms 18 are drawn against the outer faces 22 of the brackets 16, thus clamping the arms rigidly in position.

26 The roving passes over only a portion of the periphery of the guide rod 15. When this portion becomes worn it is desirable that the rod be turned about its axis to present another portion of its area. To provide for this 40 adjustment the rod 15 may be, therefore, loosely fitted in its supporting arms 18 and normally secured against rotation by means of one or more set screws 26.

Screws 23 are mounted vertically in slots 45 20 and have screw-threaded engagement with the inner ends of the arms 18. The heads of the screws 23 bear against the upper walls of the slots 20, while the lower ends of the screws bear against the bottom walls of the 50 slots 20. The heads of the screws are provided with screw-driver slots 24 into which a screw-driver may be inserted through apertures 25 which are somewhat smaller than 55 and located directly above the heads of the screws. To accomplish the vertical adjustment of the arms 18 and thereby properly position the rod 15, the screws 23 are rotated by means of a screw-driver inserted in the 60 apertures 25. Since the screws have threaded engagement with the arms 18 and are themselves confined against vertical movement, the arms 18, after being released by loosening the nuts 21, are caused to move 65 within the slot 20. When the correct adjust-

ment is secured, the nut 21 is again tightened, thus securing the arms rigidly.

While it is immaterial in what manner the roving is caused to have relative movement along the rod 15, the present invention illustrates a desired construction wherein such traversing is accomplished in a novel and effective manner by traversing the twister tubes, which function as traveling guide-eyes. The twister tubes are moved simultaneously by a suitable traversing mechanism, which is connected to the support 13. As the tubes are traversed, the contact point of the roving upon the guide rod is constantly changing throughout the length of the traversing movement. The wear upon the rod is thus distributed over a substantial portion of its area.

In conformity to the usual practice in machines of the type herein presented two rows of twister tubes are provided. There are consequently two tube supports 13 which must be reciprocated to produce the desired traverse. Upon the ends of the tube supports 13 are secured especially constructed connector blocks 27 by means of which the movement of the outer ends of the levers 28 and 29 is transmitted to the supports 13. The levers 28 and 29 are fulcrumed upon the frame of the machine at 30 and 31 respectively. The inner ends of the levers are provided with followers 32 and 33 which are received in a cam slot 34 in the cam disk 35.

The cam disk 35 is preferably driven from some rotating element of the machine. As shown herein the disk is provided with teeth on its circumference which are engaged by a worm 36 mounted on a shaft 37 which is rotatably mounted in the frame of the machine. The shaft 37 has mounted thereon a worm gear 38 which is driven by a worm 39 on the drawing roll 5. The contour of the cam slot, therefore, determines the extent of traverse of the twister tubes while power to traverse the tubes is obtained from the drawing rolls.

When a coarse yarn is being spun or a silk yarn in a machine not embodying the invention, a groove is rapidly worn in the roving guide. The present invention entirely eliminates the formation of such grooves, and enables a guide rod to be maintained in service for a period of time greatly in excess of those in use under existing conditions.

Having thus described the invention, what is claimed as new, and desired to be secured by Letters Patent, is:

1. In a spinning frame, feed rolls, drawing rolls co-operating therewith to produce draft in the roving, a plurality of twister tubes through which the roving is threaded acting to produce false twist therein, a plurality of supporting arms, a guide rod rotatably supported therein extending longitudinally of the machine over which the roving passes

acting to direct the roving to the twister tubes, means operable to secure the guide rod against rotation and means acting to move said twister tubes relatively to the guide rod 5 whereby the point of contact of the roving with the guide rod is constantly changed and the guide rod may be rotatably adjusted to present a new wear surface.

2. In a spinning frame, feed rolls, drawing 10 rolls co-operating therewith to produce draft in the roving, a plurality of twister tubes through which the roving is threaded acting to produce false twist therein, a plurality of 15 vertical adjustable supporting arms normally fixed in position, a guide rod rotatably supported in said arms acting to direct the roving to the twister tubes, a plurality of set screws having screw-threaded engagement with said arms operable to secure the rod 20 against rotation and automatic means acting to reciprocate said twister tubes longitudinally of the guide rod whereby the point of contact of the roving with the guide is constantly changed throughout a predetermined 25 portion of the length thereof and the guide rod may be rotatably adjusted to present a new wear surface.

In testimony whereof, we have signed our names to this specification.

30 SAMUEL F. ROCKWELL.
